UNITED STATES PATENT OFFICE

165,550

ELECTRIC TYPEWRITER

Lawrence Richard Prouty, New York, N. Y.

Application September 3, 1947, Serial No. 141,190

Term of patent 3½ years

(Cl. D64—11)

To all whom it may concern:

Be it known that Lawrence Richard Prouty, a citizen of the United States of America, residing at New York, in the county and State of New York, has invented a new, original, and ornamental Design for Electric Typewriters, of which the following is a specification, reference being had to the accompanying drawing, forming a part thereof.

The figure is a front perspective view of an electric typewriter, showing my new design.

I claim:

The ornamental design for an electric typewriter, as shown.

LAWRENCE RICHARD PROUTY.
